Ralph John Carney

UNITED STATES PATENT OFFICE.

RALPH JOHN CARNEY, OF BOSTON, MASSACHUSETTS.

SCARFPIN.

Application filed January 21, 1921. Serial No. 438,973.

To all whom it may concern:

Be it known that I, RALPH JOHN CARNEY, a citizen of the United States, residing at Boston, in the county of Suffolk and Commonwealth of Massachusetts, have invented 5 a new and useful Scarfpin, of which the following is a specification.

My invention relates to an improvement in scarf-pins; and its object is to provide 10 a scarf-pin which cannot be easily stolen from the scarf of the wearer or lost therefrom.

I attain this object by the construction illustrated in the accompanying drawing, 15 in which—

Figure 1 is a back view of a scarf-pin; Fig. 2 is a vertical section through said scarf-pin.

Similar letters refer to similar parts 20 throughout the several views.

The cup-plate *a*, which forms the back of the head of the scarf-pin is rigidly fastened at the end of the shank *b*, said shank *b*, is bent at right angles a short distance from said cup-plate *a*. The ornamental plate *c*, and the disc *e*, are rigidly fastened 25 to each other and form the face member of the head of said scarf-pin. The smaller loop of the curved prong *d*, is soldered to the disc *e*; said face member is then loosely secured upon the cup-plate *a*, in such a manner that it may revolve thereupon. The point of the curved prong *d*, passes through 30 the opening *f*, in the cup-plate *e*. The larger loop of said curved prong *d*, is free 35 to emerge from the opening *f*, when said face member is revolved in the direction of the point of said curved prong *d*, but the bend *h*, in curved prong *d*, by coming in contact with the depression *g*, in the cup-plate 40 *a*, prevents said point of the curved prong *d*, from being entirely withdrawn from the opening *f*, when said head member is revolved in an opposite direction.

When the scarf-pin is ready to be put in place the point of the curved prong *d*, rests 45 against the outside of the depression *g*, but does not project beyond the main outside surface of the cup-plate *a*. After the scarf- 50 pin has been put in place in the scarf, the ornamental plate *c*, by being revolved in the direction of the point of said curved prong *d*, will cause said curved prong *d*, to

enter the scarf after the manner of a corkscrew, thus holding said scarf-pin in place. 55 Said curved prong *d*, may obviously be removed from said scarf by a revolution of the ornamental plate *c*, in an opposite direction.

I am aware that prior to my invention 60 there have been scarf-pins with a prong designed to hold them in place in the scarf. I therefore do not claim such a scarf-pin broadly; but

I claim:

1. A scarf pin comprising in combination a shank, a back head member rigidly secured to one end of said shank, a front head revolvably mounted on said back head member, a spring prong fastened to said front 70 head and passing through an opening in said back head member, said prong curved to advance and retract the end thereof when said face member is turned in opposite direction relative to said back head member. 75

2. A scarf pin comprising in combination a shank, a back head member, a front head member, one of said members rigidly secured to said shank, and the other of said members mounted for turning movement 80 relative thereto, a prong fastened to said front head member and passing through an opening in said back head member, said prong curved to advance and retract the end thereof when one of said members is turned relative to the other.

3. A scarf pin comprising in combination a pin portion, a head mounted for turning movement relative to said pin portion, a back plate interposed between said head and said pin portion and secured to the latter, and a prong mounted for advance and retractile movement through said back plate. 90

4. A scarf pin comprising in combination a pin portion, a head and a second part carried by said pin portion means permitting relative turning movement between said head and said second part, and a prong actuated by turning of said head relative to said pin mounted for advance and retractile movement relative to said head. 95

5. A scarf pin comprising in combination a pin portion, a head and a second part carried by said pin portion, means permitting relative turning movement between 100 105

said head and said second part, and a resilient prong mounted for advance and retractile movement relative to said head.

6. A scarf pin comprising in combination a pin portion, a head and a second part carried by said pin portion, means permitting relative turning movement between

said head and said second part, and a resilient curved prong mounted for advance and retractile movement relative to said head.

RALPH JOHN CARNEY.
